UNITED STATES PATENT OFFICE.

GUSTAVE H. SCHMIDT, OF ALHAMBRA, CALIFORNIA.

RUBBER HEEL FOR SHOES.

Application filed May 12, 1926, Serial No. 108,670, and in Germany February 27, 1926.

My invention relates to rubber heels for shoes, and a purpose of my invention is the provision of an extremely simple and inexpensive device capable of being readily applied to the heels of shoes by which a relatively thin and inexpensive layer of rubber can be secured to the heel to function as a rubber heel and which is easily detached from the shoe when worn to permit substitution of a new layer of rubber or the interchanging of the layer with that of the other shoe.

I will describe only one form of rubber heel embodying my invention, and will then point out the novel features thereof in claims.

In the accompanying drawings,

Figure 1 is a view showing in bottom plan and with a portion thereof broken away one form of rubber heel embodying my invention in applied position to the shoe;

Figure 2 is a vertical sectional view taken on the line 2—2 of Figure 1;

Figure 3 is a horizontal sectional view taken on the line 3—3 of Figure 2;

Figure 4 is a transverse sectional view taken on the line 4—4 of Figure 1.

Referring specifically to the drawings, my invention, in its present embodiment, comprises an attaching plate A of the same contour as the shoe heel H and constructed of metal or other suitable inelastic material so as to constitute a relatively thin layer in its association with the shoe heel. This attaching plate is permanently secured to the heel H by screws 15 or other suitable fastening members, and it is provided on that side confronting the heel H with a pair of channels 16 which extend inwardly from the forward edge of the plate and in converging relation to each other. The channels terminate in spaced relation to the rear edge of the plate and, hence, their rear ends are closed but their forward ends are open, even with the plate in attached position to the shoe heel, to permit the insertion into the channels of a fastening member indicated generally at F.

Constituting the bottom layer of the shoe heel is a relatively thin layer R of rubber or other suitable elastic material which is adapted to be detachably secured to the attaching plate A, its elasticity producing in its association with the shoe heel the effect of a rubber heel. This plate R has partly embedded therein a plurality of studs 17

having relatively large heads 18. The studs extend upwardly through suitable openings 19 formed in the bottom wall of the channel 16 so that the heads 18 are disposed within the channel and more particularly within recessed portions 16^a of the channels. With the studs in this position, the rubber layer can be fixedly secured to the attaching plate through the application of the fastening member F. This member comprises a single length of resilient wire bent substantially in the form of a U to provide converging portions 20 connected at one end by an intermediate portion 21. The free ends of the portions 20 are extended and bent rearwardly to provide resilient fastening portions 22 which have arcuate portions 22^a at points corresponding to the positions of the studs 17 so as to accommodate the shanks of the latter. In applying the fastening member F, the portions 20 are extended into the channels 16 to the position shown in Figure 3, wherein the arcuate portions 22^a move into engagement with the studs 17 at points beneath the heads 18, and because of the resiliency of the portions 22 they tend to hold the arcuate portions in engagement with the studs so as to prevent accidental removal of the fastening member from the channels, and further to hold the stud heads 18 against downward movement through the openings 19 so that the rubber heel R is firmly secured in contiguous relation to the attaching plate A. Edgewise movement of the rubber heel R on the attaching plate is prevented through the provision of a tongue and groove connection 23 between the two plates.

When the rubber heel R becomes worn or loses its elasticity, it can be readily detached from the attaching plate by removal of the fastening member F. The member F can be removed by pulling outwardly upon the exposed portion 21, thus releasing the studs 17 so that they may be withdrawn through the openings 19 in the removal of the rubber heel from the attaching plate. Where the rubber layers become worn in the usual manner in a pair of shoes, my invention permits the detaching of the two layers from the two heels of a pair of shoes and the interchanging of the layers, as will be understood.

Although I have herein shown and described only one form of rubber heel for shoes embodying my invention, it is to be understood that various changes and modi-

fications may be made therein without departing from the spirit of the invention and the spirit and scope of the appended claims.

I claim as my invention:

5. 1. A heel for shoes comprising a plate having open ended channels therein and openings communicating with the channels, a second plate, headed studs on the second plate extending through the opening of the 55 first plate and into the channels, and a fastening member constructed from a single length of wire bent substantially in the form of a **U** having portions inserted into the channels, a portion connecting said portions 60 and disposed exteriorly of the plates, and resilient portions on said portions engaging the shanks of the studs beneath their heads to thereby detachably secure the first plate to the second plate.
10. 2. A heel for shoes comprising a plate adapted to be permanently secured to the heel portion of a shoe and having its upper surface provided with a pair of longitudinally extending channels, the forward ends 65 of which are open and the rear ends closed, the lower surface of the plate having a plurality of openings communicating with the channels, a second plate having headed studs projecting upwardly therefrom and extending through said openings to dispose their heads and a portion of their shanks in said channels, and a fastening member of substantially **U** form having resilient portions 70 inserted into the channels beneath the heads of the studs so as to engage the shanks of the latter, and a portion connecting the resilient portions disposed exteriorly of the plates and adapted to be 75 gripped in applying and removing the member, said resilient portions flexed under engagement with the shanks of the studs, to thereby detachably secure the second plate to the first plate.
15. 3. A heel for shoes comprising a plate having channels therein and openings communicating with the channels, a second plate, headed studs on the second plate extending through the openings of the first 80 plate and into the channels, and a fastening member having resiliently connected portions inserted into the channels beneath the heads of the studs and engaging the shanks of the latter, the resilient portions being 85 flexed under their engagement with the studs, to thereby detachably secure the first plate to the second plate.
20. 4. A heel for shoes comprising a plate having channels therein and openings communicating with the channels, a second plate, headed studs on the second plate extending through the openings of the first plate and into the channels, and a fastening member of substantially **U** form having resilient portions 90 inserted into the channels beneath the heads of the studs so as to engage the shanks of the latter, and a portion connecting the resilient portions disposed exteriorly of the plates and adapted to be 95 gripped in applying and removing the member, said resilient portions flexed under engagement with the shanks of the studs, to thereby detachably secure the second plate to the first plate.
25. 5. A heel for shoes comprising a plate having channels therein and openings communicating with the channels, a second plate, headed studs on the second plate extending through the openings of the first plate and into the channels, and a fastening member having resiliently connected portions inserted into the channels beneath the heads of the studs and engaging the shanks of the latter, the resilient portions being 95 flexed under their engagement with the studs, to thereby detachably secure the first plate to the second plate.

GUSTAVE H. SCHMIDT.
